UNITED STATES PATENT OFFICE.

PAUL T. ZIZINIA, OF NEW YORK, N. Y.

GARMENT-HANGER.

977,921.

Specification of Letters Patent. Patented Dec. 6, 1910.

Application filed January 25, 1910. Serial No. 539,931.

To all whom it may concern:

Be it known that I, PAUL T. ZIZINIA, a citizen of the United States, and residing at New York, in the county of New York and 5 State of New York, have invented certain new and useful Improvements in Garment-Hangers, of which the following is a specification, such as will enable those skilled in the art to which it appertains to make and 10 use the same.

This invention relates to garment hangers and the object thereof is to provide an improved device of this class particularly designed for supporting or suspending trousers, but which may also be employed for supporting or suspending folded coats, dresses and other garments or articles.

The invention is fully disclosed in the following specification, of which the accompanying drawing forms a part, in which the separate parts of my improvement are designated by suitable reference characters in each of the views, and in which;

Figure 1 is a plan view showing my improved garment hanger in position for use and showing the method of connecting it with the door of a wardrobe or other support, a part of the latter being shown in section, and;— Fig. 2 a side view of the device as shown in Fig. 1 and showing also the suspending part thereof in different positions, one of which is shown in dotted lines.

In the drawing forming part of this specification, I have shown at *a* a support which may be a wall or the door of a room, or of a wardrobe, or a part of the interior of a wardrobe or any other device or article with which my improved garment hanger may be 40 connected; and in the practice of my invention I provide two similar blocks *b* which are adapted to be held in parallel position and a cross block *c* which is secured transversely of the blocks *b* by screws *d*, which

45 are passed through the block *c* and through the blocks *b* into the door or other support *a* as clearly shown. The block *c* is provided in its inner face with an oblong recess *c*² in which the blocks *b* fit, and centrally of its 50 inner face with a deeper recess *c*³ and said blocks *b* are provided with a transverse pin, bolt or screw *b*² which passes therethrough. I also provide a bar or arm *e*, one end of 55 which is adapted to fit between the blocks *b* and to move between said blocks and said end of the bar or arm *e* is provided with a

longitudinal slot *e*² through which the pin, bolt or screw *b*² passes. The bar or arm *e* is provided with a plurality of rods *f* which are passed therethrough and project at both sides thereof and on which, in practice, the trousers or other garments are hung as indicated by dotted lines in Fig. 2, and the bar or arm *e* may be held in a horizontal position, as shown in Figs. 1 and 2, or may be raised into a substantially vertical position, as indicated by dotted lines in Fig. 2. In order to raise the bar or arm *e* from the horizontal position shown in Fig. 2 it is only necessary to raise the outer or free end thereof and the inner end thereof, in this operation, will drop downwardly between the blocks *b* to a predetermined point as indicated in said figure, the pin, bolt or screw *b*² moving in the slot *e*² and forming a stop 65 to limit the downward movement of said bar or arm. Whenever it is desired to place the bar or arm *e* in a horizontal position as shown in Figs. 1 and 2, the said bar or arm is lifted vertically and lowered into a horizontal position and in this operation the pin, bolt or screw *b*² moves backwardly in the slot *e*² and the downward movement of the said bar or arm is limited by the transverse member or block *c*, and pin. 70

In practice the rods *f* are preferably passed through the bar or arm *e*, said bar or arm being provided with transverse apertures *e*³ for this purpose and said rods and apertures are so made that the rods will 80 closely fit in said apertures but may be removed or detached from said bar or arm whenever necessary for packing or other purposes, and the parts *b* and *c* are also 85 preferably made separately for a similar purpose.

With the construction shown and described the distance between the transverse pin *b*² on which the arm *e* is mounted and the wall or support *a* is greater than the 100 thickness of one side of the end portion of said arm formed by the longitudinal slot *e*², and by reason of this construction when the arm *e* is raised into an upright position as shown in dotted lines in Fig. 2, the upper 105 end portion thereof is held at an angle to said wall or support and does not press thereon or rest in contact therewith, and the position of the pin *b*² above the cross block or member *c* is also such as to permit the arm *e* 110 to be lowered into a horizontal position.

This device is primarily intended for a

support for trousers and may be used in either of the positions shown and indicated in Fig. 2 and it may also be used for supporting and suspending any other kind or 5 class of articles and changes in and modifications of the construction described may be made within the scope of the appended claim without departing from the spirit of my invention, or sacrificing its advantages.

10 Having fully described my invention, what I claim as new, and desire to secure by Letters Patent, is:—

15 A hanger of the class described comprising two main block members held in parallel position, a cross block member placed transversely of said main block member and recessed longitudinally to receive the same, screws passed through said transverse block member and through said main block members 20 for securing the hanger to an upright

support and holding the main block member in parallel position, said main block members being provided with the transverse block member and rearwardly thereof with a transverse pin, an arm one end portion of 25 which is freely movable between said main block members and provided with a longitudinal slot through which said pin passes whereby said arm may be held in a horizontal or upright position and rods passed through 30 and removable from said arm.

In testimony that I claim the foregoing as my invention I have signed my name in presence of the subscribing witnesses this 18th day of January 1910.

PAUL T. ZIZINIA.
